WILLIAM W. BRADSHAW, OF HARRINGTON, DELAWARE.

HAMMOCK ATTACHMENT.

1,145,290.

Specification of Letters Patent.

Patented July 6, 1915.

Application filed January 6, 1914. Serial No. 810,617.

To all whom it may concern:

Be it known that I, WILLIAM W. BRADSHAW, citizen of the United States, residing at Harrington, in the county of Kent and 5 State of Delaware, have invented certain new and useful Improvements in Hammock Attachments, of which the following is a specification.

This invention relates to new and useful 10 improvements in hammock attachments, and aims particularly to provide a novel form of wire frame which may be readily attached to any ordinary form of hammock for supporting a mosquito netting above the occupant of the hammock so that he will be thoroughly protected against insects.

A further object of the invention is to construct the wire frame in such manner that it may be cheaply manufactured, will 20 be durable and efficient in its action, and may be readily attached to and detached from any standard form of hammock.

The above and additional objects are accomplished by such means as are illustrated 25 in the accompanying drawings, described in the following specification, and then more particularly pointed out in the claims which are appended hereto and form a part hereof.

With reference to the drawings, wherein 30 there has been illustrated the preferred embodiment of this invention as it is reduced to practice, and throughout the several views of which similar reference numerals designate corresponding parts, Figure 1 is a perspective view showing the supporting frame and netting in assembled relation to a hammock; Fig. 2 is a perspective view illustrating in detail the preferred embodiment of clamp which is employed in holding the 35 40 terminal supports of the bridge wire in the desired position at the ends of the hammock; and Fig. 3 is a detail view illustrating a modification of the clamp of Fig. 2.

Taking up the detail description of the 45 drawings, and referring particularly to Fig. 1, in which the invention is best illustrated as an entirety, the numeral 10 designates a hammock which may be suitably suspended between a pair of trees as by ropes 11, or 50 any other desired means.

As previously set forth, the present in-

vention consists essentially in providing a frame which may be readily attached to the hammock for holding a mosquito netting above the occupant to shield him from insects and the like. In Fig. 1 the mosquito netting is designated by the letter A. In holding this netting in the proper position above the hammock, this invention employs 55 a bridge wire 12 and a pair of terminal supports 13 and 14. The bridge member 12, as its name indicates, spans the space between the two terminal supporting members 13 and 14. In its preferred embodiment, the member 12 is formed from two strands of 60

relatively heavy wire which are twisted one about the other at their center portions, as indicated at 15, so that they will be held in the desired relation to one another at all times. The free terminals 16, 17, 18 and 19 70 of the two wires forming the bridge member are directed diagonally away from the portion 15 for a portion of their length, but are bent at their extreme terminals to extend in parallel relation to each other, as indicated at 20, 21, 22 and 23, respectively. The members 20, 21, 22 and 23 are bent to produce terminal eyelets, as at 24. These 75 eyelets are engageable with the receiving extensions 25 which are formed on the supporting members 13 and 14. The members 13 and 14 are substantially identical in their construction, and it is deemed necessary, therefore, to describe only one of them in detail, the member 13 being chosen 80

in this instance. As will be readily observed upon reference to Fig. 1, the member 13 consists of an inverted U-shaped body portion which is formed from a single length of wire. The horizontal or bight portion of the member 13 is designated by the numeral 26, while the arms of the U are designated by the numerals 27 and 28. At the junction of the members 27 and 28 with the bight or horizontal portion 26 are formed the extensions 25 which are produced by merely bending upon itself the wire from which the member 13 is constructed. The lowermost portion of the arms 27 and 28 of the terminal supporting member are bent at right 90 angles to produce the clamp axles 29. These 95 axle members 29 are each adapted to re-

ceive the two jaws of a clamp and extend along the edge of the hammock when the clamps are applied in the manner to be hereinafter explained.

5 Reference will now be had to Fig. 2, in which is illustrated the preferred form of clamp employed in holding the arms 27 and 28 in position at the terminals of the hammock. This clamp includes two co-acting 10 jaw members, individually designated by the numerals 30 and 31. The member 31 is formed from a single length of resilient wire, and in its manufacture is first bent in the shape of a U, the arms 32 and 33 of this 15 U being then bent as at 34 to extend rearwardly from the bight portion 35. Intermediate their length, these arms are formed with an additional lateral U, as at 36. The extreme terminal of the arm 32 is wound 20 about the vertical portion of the member 28, as indicated at 37, while the terminal of the arm 33 is wound about the outer terminal of the axle 29, as indicated at 38. The clamp jaw 30 is also formed from a single length 25 of resilient wire, being bent to produce a bight portion 39 and a pair of arms 40 and 41. The bight portion 39 of the clamp member 30 is greater in length than the bight portion 35 of the member 31, while 30 the arms 40 and 41 are bent toward each other to lie interiorly of the arms 32 and 33 when the clamping members are in closed position. It may be well to observe at this 35 point that the bight portion 35 of the jaw 31 is bowed inwardly toward the axle 29. The purpose of this formation will be later explained. The terminals of the arms 40 and 41 are wound about the axle 29, as indicated at 42, producing eyelets which are free 40 to rotate on the axle.

It will be seen that by swinging the jaw 30 on its axis 29, the bight portion 39 may be disposed to lie beneath the bight portion 35 of the member 31 so that it will be lodged 45 in the elbows formed as at 34 in the arms 32 and 33. The purpose obtained in making the bight portion 39 of greater length than the member 35, and in forming the additional U 36 will now become apparent, for 50 it will be seen that being of greater length than the member 35, the member 39 will be limited in its swinging movement by the arms 32 and 33, and will be held in clamping relation to the member 35 by engaging in 55 the elbows 34. It will also be seen that the arms 40 and 41 will be disposed in clamping relation to the additional U 36 when the two members 30 and 31 are in closed position, as in Fig. 2.

60 In applying the clamp to the hammock, it is only necessary to separate the jaws, disposing the member 31 below the fabric of the hammock, and the member 30 above the fabric. Upon swinging the member 30 on 65 its axle 29, the cloth or fabric of the ham-

mock will be tightly clamped between the members 39 and 35 and the arms 40 and 41 and U members 36.

Relative to the application of the clamp to the hammock, it is desirable to emphasize 70 the fact that the extreme terminals of the bight portion 39 extending as they do beyond the arms 32 and 33 of the clamp 30 form in effect finger grips which materially facilitate the operation of applying or 75 removing the clamp.

In Fig. 3 there is illustrated a modified form of clamp. This modified form is similar to the preferred form with but one exception. It is provided at an approximate 80 center portion of the bight member 35 with an upwardly extending lip or finger member 43. It will be obvious that the member 43 will be of material aid when the operator desires to disconnect the two jaws in 85 removing the clamp from the hammock.

Referring now again to Fig. 1, it will be seen that the two end frames 13 and 14 are secured to opposite terminals of the hammock by the application of the clamps which 90 are carried by the lower portion. It then remains to properly position the bridge wire 12 by applying its terminal loops 24 to the retaining projections 25. The mosquito netting A is then draped over the frame, thus 95 formed by the members 12, 13 and 14, consequently protecting the occupant of the hammock from insects and the like.

While the netting A may be applied to the frame by being merely draped thereon, as 100 above explained, it has been found preferable in most instances to apply it in the manner shown in Fig. 1. In this figure, it will be observed that the portions 20, 21, 22 and 23 of the member 12 are passed through 105 small openings formed adjacent the terminal portions of the netting, as indicated at 44.

Inasmuch as the member 12 is constructed of two lengths of resilient wire, it will be seen that the members 20 and 21 and 22 and 23 will, by reason of the resiliency of the wires, be held in engagement with the member 25 without liability of displacement when the hammock is swung in the well known manner. A further advantage to 110 which particular attention is directed is that resulting from providing clamping members which are formed with relatively long jaws. By making the jaws relatively 115 long, it is obvious that the end supporting frames 13 and 14 will be securely held in the desired vertical relation to the hammock and will not be liable to tilt out of their proper position as they might were the clamps relatively short.

In reduction to practice, it has been found that the form of this invention illustrated in the drawings, and referred to in the above description as the preferred embodiment, is the most efficient and practical; yet realizing 120 125 130

that the conditions concurrent with the adoption of this device will necessarily vary, it is desirable to emphasize the fact that various minor changes in details of construction, proportion and arrangement of parts may be resorted to, when required, without sacrificing any of the advantages of this invention as defined in the appended claims.

What is claimed is:

- 5 1. In a hammock attachment of the class described, a canopy support including standards each provided with an attaching clamp including relatively broad and flat clamping members arranged for clamping engagement with the marginal portion of the flexible bed of a hammock.
- 10 2. In a hammock attachment of the class described, a canopy support including standards, each provided with an attaching clamp having relatively broad clamping members arranged to clamp the marginal portion of the flexible bed of a hammock, and rigid means connecting and bracing the said standards.
- 15 3. In a hammock attachment of the class described, a canopy support including spaced standards, each provided with an attaching clamp including relatively broad pivotally connected members, the said clamps having their open sides presented toward each other and being arranged to clamp opposite marginal portions of the flexible bed of a hammock, and means connecting the upper ends of the said standards.
- 20 4. In a hammock attachment of the character described, a bridge member consisting of two strands of resilient wire twisted one about the other for a portion of their length and having their free terminals directed outwardly and angularly with respect to their twisted portions and then bent to extend in parallel spaced relation, and eyelets formed on the extreme terminals of the strands, a pair of terminal supporting frames 40 for the bridge member, projections carried by the upper terminals of the supporting frame and adapted to receive the eyelets of the bridge member, and clamps carried by the supporting frames whereby they may be detachably secured to the hammock.
- 45 5. In a hammock attachment of the character described, a bridge member formed of resilient wire, terminal supporting frames for the bridge member, each of said supporting frames including a substantially U-shaped body member having the lower portions of its arms bent at right angles forming axles, a pair of clamping jaws secured to each of the axles, one of said jaws being relatively fixed and the other of said jaws being mounted for swinging movement, said clamping jaws being adapted to detachably secure the terminal frame members to the hammock.
- 50 6. In a hammock attachment of the char-

acter described, a pair of supporting frames, a bridge member carried by the frames, a cover adapted to be draped over the bridge member and supporting frames, a pair of clamping jaws carried by the lower terminals of each frame, and yieldable means for locking the jaws in clamping relation.

7. In a hammock attachment of the character described, a pair of supporting frames, a bridge member carried by the frames, a cover adapted to be draped over the bridge member and supporting frames, a pair of clamping jaws carried by the lower terminals of each frame, each clamping member consisting in a substantially U-shaped fixed jaw, a substantially U-shaped movable jaw, and yieldable means carried by the fixed jaw and engageable with the movable jaw for yieldably locking the jaws in clamping relation.

8. In a hammock attachment of the character described, a bridge member, supporting frames detachably connected to the terminals of the bridge member, a cover adapted to be draped over the bridge member and supporting frames, and a plurality of clamping members for detachably securing the frames to the flexible body portion of a hammock, each of said clamping members including a fixed jaw of substantially U-shaped conformation, the arms of the fixed jaw being bent to produce inwardly extending U-shaped portions, and a movable jaw having its arms curved to engage intermediate their length with the said inwardly extending U-shaped portions when the jaws are in clamping relation.

9. In a hammock attachment of the character described, a bridge member, supporting frames detachably connected to the terminals of the bridge member, a cover adapted to be draped over the bridge member and supporting frames, and a plurality of clamping members for detachably securing the frames to the flexible body portion of a hammock, each of said clamping members including a fixed jaw of substantially U-shaped conformation, the arms of the fixed jaw being bent to produce inwardly extending U-shaped portions, and a movable jaw having its arms curved to engage intermediate their length with the said inwardly extending U-shaped portions when the jaws are in clamping relation, and resilient means carried by the fixed jaw and engageable with the movable jaw for holding the jaws in clamping relation.

10. In a hammock attachment of the character described, a bridge member, supporting frames detachably engaged with the bridge member, a covering draped over the bridge member and supporting frames, and a clamp carried by each frame for detachably securing the frames to the flexible body portion of a hammock, each of said clamps

including a substantially U-shaped fixed jaw and a substantially U-shaped movable jaw, the arms of said fixed jaw being bent upon themselves to dispose the bight portion of the jaw so that it intersects the arms at a point intermediate their length whereby the bight portion of the fixed jaw may be engaged over the bight portion of the movable

jaw for yieldably holding the jaws in clamping relation.

In testimony whereof I affix my signature in presence of two witnesses.
